UNITED STATES PATENT OFFICE.

FRANK J. W. WEISER, OF ELMHURST, ILLINOIS.

PLAYER-PIANO.

1,351,312.

Specification of Letters Patent. Patented Aug. 31, 1920.

Application filed July 10, 1919. Serial No. 309,827.

To all whom it may concern:

Be it known that I, FRANK J. W. WEISER, a citizen of the United States, residing at Elmhurst, in the county of DuPage and State of Illinois, have invented certain new and useful Improvements in Player-Pianos, of which the following is a specification, reference being had therein to the accompanying drawing.

My invention relates to player pianos, its object being to provide a flexible spring contact attached to the action sticker and to be struck by the striker rod when the player pneumatic operates, whereby the player action is not subjected to sudden stress or blows and the stroke of the hammers on the strings is easier and more like that resulting from the human touch on the keys and the parts controlling the action of the pneumatic on the stickers are in view above the pneumatic and in front of the player action.

The invention consists in the matters hereinafter set forth and then pointed out in the claims.

In the accompanying drawing Figure 1 is a view in side elevation of a player-piano action equipped with my invention, the parts being in their position of rest and portions of the piano action frame being in section;

Fig. 2 is a similar view with the parts in their position of action, and Fig. 3 is a detail view.

In the drawings the numerals 5 and 6 dictate usual longitudinal rails of the piano action frame, 7 the customary wippen pivotally hung at its rear end by the flange 8 to the rail 5, and 9 the usual wooden sticker pivotally connected at its upper end as at 10 to the associated wippen 7 and pivotally hung at its lower end to the link 11 which is pivotally attached to the rail 6. The wippen is provided with the upper bracket 12 to which the lower end of the associated jack 13 is pivoted, the offset heel 14 of the jack being engaged by the coil spring 15 seated on the wippen and reacting between these parts. The upper end of the jack operates upon the associated hammer 16 which is pivoted at its butt to the rail 5 in the usual manner, and carries the customary cushioned bumper 17 which is struck by the corresponding cushioned back-check 18 carried on the associated wippen 7; the hammer butt has the usual bridle tape 19 whose outer end is connected to the bridle wire 20.

The blocker rail 21 extends across the front ends of the wippens, and the regulating rail 22 extends across the heels of the jacks.

The parts so far described constitute the usual parts of a regular piano action, it being understood that when the sticker 9 is raised by the stroke of the associated key (not shown) the head of the hammer 16 strikes the string S.

The player pneumatic 23 carries the striker-rod having an adjustable screw cap 24 which passes freely through the guide 25. A flexible spring contact is secured to the sticker 9 in the path of the cap and is adapted to be raised by it when the pneumatic 23 collapses. In the present form this contact is formed by a strip of flexible spring metal whose attaching body 26 is secured to the sticker above the pneumatic and whose projecting arm 27 overlies the cap. The body 26 may be attached to the sticker by the pair of screws 28 as shown in Figs. 1 and 2, or by bending its lower end to fit in a kerf in the sticker and using a single screw as shown in Fig. 3; in any case the body 26 preferably is outwardly curved or bowed between its points of connection with the sticker to prevent its loosening and the screw from rattling as the flexibility of its bow compensates or takes up the expansion and contraction of the wood of the sticker as the latter expands or contracts under varying conditions of heat and cold.

When the player pneumatic collapses in its operation the cap presses upon and raises the flexible spring arm and operates the piano action to cause the hammer to strike its string. The flexible spring arm cushions the sudden stress or blow of the cap on the piano action and its flexibility relieves the action from the jar and shock of the stroke and transmits the stroke of the screw gradually and with a flexible or springy action or contact similar to the flexible or springy touch of the fingers on the keys when the piano is played by hand. The result is that the sticker is raised and the hammer is operated by a stroke or action that is essentially and practically similar to that obtained by the human touch.

The spring-contacts are attached to the front of the stickers above the pneumatic with their arms extending forwardly at the front of the player action, and the adjustable caps are in line with the arms and also above the pneumatic, so that these co-acting

parts between the pneumatic and the stickers are accessible and in plain view from the front of the device and, above the pneumatic, thus enabling the mechanic to operate at the front of the device and with all the co-operating parts in plain sight when truing up the caps to level them up to the contacts to eliminate lost motion between these parts and insure uniform action of the pneumatic on the stickers. By this construction this adjustment can be determined by the sense of sight of the mechanic, and so the regulation of the action of the pneumatic on the stickers is positive and accurate, and also can be accomplished without varying the positions or tensions of the spring arms so that uniform and equal spring action of the arms on the stickers is assured.

I claim:

20 1. In a player piano, a piano action including a hammer and its operating sticker, a player pneumatic having an adjustable

cap located in front of the sticker and above the pneumatic, and a contact consisting of a flange attached to the front side of the 25 sticker and a flexible spring arranged above the pneumatic and in the path of the cap.

2. In a player piano, a piano action including a hammer and its operating sticker, a player pneumatic having an adjustable 30 cap located in front of the sticker and above the pneumatic, and a contact arranged above the pneumatic consisting of an outwardly bowed spring body fixed to the front of the sticker at each side of its bow and a spring 35 arm projecting forwardly from the body into the path of the cap.

In testimony whereof I affix my signature in presence of two witnesses.

FRANK J. W. WEISER.
